Attorneys

UNITED STATES PATENT OFFICE.

GEORGE EUGENE MITTINGER, OF CLEVELAND HEIGHTS, OHIO.

CRIMPING TOOL.

Application filed July 12, 1923. Serial No. 651,077.

To all whom it may concern:

Be it known that I, GEORGE E. MITTINGER, a citizen of the United States, residing at Cleveland Heights, in the county of Cuyahoga and State of Ohio, have invented certain new and useful Improvements in Crimping Tools, of which the following is a specification, reference being had therein to the accompanying drawing.

10 My invention relates to an improvement in a crimping tool which is particularly designed for crimping or fastening in the heads or covers of metallic kegs, barrels, or the like.

15 My present invention relates to a crimping tool particularly adapted to crimp or fasten a one-piece cover or head in the central ring opening of a keg or barrel. I have found that for certain purposes it 20 is of advantage to have a one-piece cover. In using a one-piece cover for closing the opening in a barrel end ring it is necessary to provide a means for fastening the cover in the ring. My improved crimping tool, 25 shown in the accompanying drawings and hereafter more particularly described, accomplishes this result.

It will be readily understood that the principle of my invention can be utilized 30 in crimping heads or covers in barrels or kegs of many kinds without departing from the spirit of the invention. The crimping heads could be very easily and readily constructed to provide a crimp of a different 35 shape should this be desired to meet with any particular use to which the tool has to be applied.

The object of my invention is to provide 40 a crimping tool so constructed as to readily and easily crimp or fasten heads or covers in metallic barrels, kegs, or the like.

Another object of my invention is to provide 45 a tool for crimping heads or covers in metallic barrels, kegs or the like, which will fasten the heads in place securely yet at the same time so fasten them that the heads can be removed when desired.

Another and further object of my invention 50 is to provide a tool for the purpose desired which is simple and cheap of manufacture and highly efficient in operation.

Other and further objects, novel features 55 and improved results of my invention will

appear in the following description and accompanying drawings.

55

In the drawings:

Figure 1 is a top view of my improved tool.

60

Fig. 2 is a view in side elevation of my improved tool.

65

Fig. 3 is a vertical sectional view of my improved tool, one of the barrel heads being shown in place upon the crimping element in full line and the extended position of the crimping elements and the crimped barrel head being shown in dotted lines.

65

Fig. 4 is a fragmentary vertical sectional view of a portion of the tool, the barrel head and barrel end ring, showing the crimping elements of the tool in extended position and the barrel head locked within the barrel head ring.

70

Referring to the drawings which show a specific form of my improved tool which is adapted to the particular work of fastening a head or cover in a barrel of the character referred to, 5 represents a hardened steel washer or base provided through its center with an opening 6 surrounded by an upwardly extending circumferential collar 7. The opening 6 of the washer or base 5 has an outwardly tapered wall 8 throughout the lower part of the depth of the opening, and said wall terminates in a vertical portion 9 adjacent to the top edge of the collar 7.

75

Mounted within the opening 6 of the base 5 and adapted to reciprocate therein is a cylindrical stud 10 of a diameter to fit 80 within the vertical wall portions 9 of the opening and be guided thereby. The lower end 11 of the stud 10 is tapered or flared outwardly as at 12.

85

Carried beneath the washer 5 are the four crimping elements or members 13, the inner edges of which have a tapered wall 14, which are in engagement with the tapered wall 12 of the enlarged head 11 of the stud 10. Due to this engagement 90 the crimping members are supported at their inner edges by the lower end of the stud while the outer ends of the crimping members are supported by four bolts 15 which 100 extend downwardly through the elongated 105 slots 16 in the base or washer 5. The lower

ends of the bolts are in screw-threaded engagement with the crimping members 13 as at 17, while the upper ends of the bolts are provided with the usual heads 18 beneath which is mounted a washer 19.

- Within the upper end 20 of the stud 10 is mounted a bolt 21 provided with the usual head 22. This bolt clamps or fastens upon the top 20 of the stud, the horizontal leg 23 of a U-shaped frame, the vertical legs 24 of which extend downwardly in separated parallel relation with the stud 10. Mounted on opposite sides of the stud 10 upon a shaft 25 which penetrates both of the vertical arms 24 of the U-shaped frame and the stud 10 are the lower cam ends 26 of the two elongated handles 27. As clearly appears in the drawings the lower cam ends 26 of the handles 27 are in engagement with an upper raised portion 28 carried by the top of the collar 7 of the base 5.

Referring now to the crimping members 13, particularly to Figs. 3 and 4 of the drawings, it will be seen that the inner edges or ends of these members are provided with an upstanding flange or collar 29 which extends upwardly into the space or cut-out portion 30 in the lower face of the base 5. To hold the crimping members in contracted position I have provided a series of coiled springs 31 which are carried in suitable openings in the base 5 and extend outwardly into the space or cut-out portion 30 where they are in engagement with the collars or flanges 29 at the inner ends of the crimping members. The action of these springs is to push in upon the collars 29 and it will be clearly seen that this pressure will hold the crimping members in contracted position.

The outer edges of the crimping members are provided with an approximately U-shaped bulge or projection 32 throughout their peripheries. The outer edge of the base 5 is provided with an L-shaped flange or seat 33 which is adapted to rest upon and receive the top edge 34 of the barrel cover. The barrel cover appears in Figs. 3 and 4 of the drawings and is approximately U-shaped having a flat bottom 35 surrounded by a vertical wall 36 which terminates in the horizontal top 34 before mentioned.

Referring now to Fig. 4 it will be seen that the horizontal top edge 34 of the barrel cover is supported upon the inner horizontal portion 37 of the barrel ring 38. Although it is not absolutely essential, the inner horizontal portion 37 of the barrel ring 38 terminates in a downwardly extending edge 39. From the foregoing description it will be seen that the enlarged lower end 11 of the stud 10 is the only connection link between the crimping members and base 5 with the U-shaped frame and the cam ended handles 27.

In operation the barrel head or cover is placed upon the supporting portion 37 of the barrel ring and the crimping members 13 are inserted upon the bottom 35 of the cover within its vertical walls 36.

During this portion of the operation the handles 27 are in a raised position and the springs 31 are functioning to hold the crimping members in contracted position.

To effect a locking of the barrel cover in place the handles 27 are grasped and pulled downwardly. As the handles are lowered, the cam ends 26 engage the upper portion 28 of the base collar 7 which moves the stud 10 upwardly. As the stud 10 rises the tapered wall 12 of its enlarged end 11 engages the inner tapered ends of the crimping members 13 and push them outwardly against the tension of the springs 31. The crimping members are guided in their outward movement by the supporting bolts 15 which slide in the elongated slots 16 in the base 5.

When the handles 27 have reached the bottom of their downward movement the crimping members 13 are in the position shown in the dotted lines in Fig. 3 and the positions also shown in Fig. 4 of the drawings. The circumferential extending portion 32 of the crimping members 13 has engaged the vertical wall 36 of the cover and crimped or bent this wall outwardly beneath the supporting wall or portion 37 of the barrel ring 38 as clearly appears at 40 in Fig. 4 of the drawings. This crimp is sufficiently great to hold the cover in the barrel ring yet it will be found that when it is desired to remove the cover that this can be effected by grasping the top edge 34 of the cover with pliers, or the like, and pulling upwardly thereupon.

From the foregoing it will be seen that I have provided a tool by which the barrel heads can be readily crimped or locked in the barrel ring. It is a rapid procedure to place the tool within the barrel cover, to press the handles of the tool once and bring them back to a raised position again. This one movement effects a complete locking of the head and the cover in the barrel ring. When the handles are brought back to a raised position the springs 31 automatically return the crimping members to a contracted position so that the tool can be removed from the cover and be ready for immediate insertion within another cover for a repetition of the operation.

It will also be readily apparent that my improved tool is simple of construction, cheap of manufacture and highly efficient in operation.

It should also be understood that the outer edge of the crimping members can be constructed to provide a crimp of any shape desired and that the tool is, there-

fore, not limited to use in the particular manner heretofore described.

Having thus described my invention what I claim and desire to secure by Letters Patent is:—

1. In a crimping tool of the class described, comprising a crimping die base, outwardly movable dies operatively connected with the said base, a vertical stud passing through the said base and having its lower end tapered and lying between the inner ends of the dies, of a cam operatively connected with the said stud and engaging the said base for relatively actuating the stud in respect to the dies and forcing the latter outward, for the purpose described.

2. In a crimping tool of the class described, comprising a die base, a stud passing vertically through the die base and having its lower end tapered, outwardly movable dies operatively connected with the said base, the tapered portion of the stud in engagement with the inner ends of the dies, and a cam operatively connected with the said stud, and means connected with the said stud and engaging the said base for imparting relative movement to the stud and the dies to force the latter outward, for the purpose described.

3. A crimping tool of the class described, comprising a die base, a plurality of outwardly movable dies operatively arranged in respect to the base, a stud extending vertically through the said base and having its lower end enlarged outwardly and lying between the inner ends of the dies, and movable means operatively connecting the said stud with the said base for causing the said relative movement between the lower end of the said stud and the said dies for forcing the latter outward, for the purpose described.

4. A crimping tool of the class described, comprising a die base, a plurality of outwardly movable dies carried by the said base, a stud extending vertically through the base and having its lower end enlarged and lying between the inner ends of the said dies, and a cam connection between the said stud and the said base to cause relative movement between the lower end of the stud and the said dies, for the purpose described.

5. In a crimping tool of the class described, comprising a die base, a plurality of outwardly movable dies operatively connected with the said base, a stud extending upwardly through the said base, a cam opera-

tively connected with the extended end of the stud, the said cam engaging the upper portion of the said base for causing relative movement between the lower end of the said stud and the said dies, for the purpose described.

6. A crimping tool of the class described, comprising a tool carrying base, a plurality of tools located in the lower portion of the said base, and a stud extending upward through the said base having its lower end enlarged and lying between the inner ends of the said dies, two oppositely extending cam levers operatively connected with the said stud and engaging the said base to cause relative movement between the lower end of the stud and said dies, for the purpose described.

7. In a crimping tool of the class described, comprising a die base, a plurality of laterally movable dies carried at the lower portion of the said base, a stud extending through the said base having its lower end tapered and lying between the inner ends of the said dies, of a cam operatively connected with the said stud and the said base to cause relative movement between its lower end and the inner ends of the said dies to force them outward, for the purpose described.

8. In a tool of the class described, a base, a plurality of crimping members supported by the base, a stud penetrating the crimping members and the base and in operative engagement with the crimping members, a yoke supported by the upper end of the stud and provided with a shaft penetrating the stud, a cam mounted upon the said shaft and in operative engagement with the base, and means to actuate the cam, for the purpose described.

9. A crimping tool of the class described, comprising a die base, a plurality of outwardly movable dies operatively connected with the lower part of the said base, a stud extending vertically upward through the said base having its lower end tapered and lying between the inner ends of the said dies, of oppositely extending cam levers located at opposite sides of the said stud, said levers engaging the top of the said base to cause relative movement between the tapered lower end of the stud and the inner ends of the dies to cause them to move outward for the purpose described.

In testimony whereof I hereunto affix my signature.

GEORGE EUGENE MITTINGER.
